DRYING APPARATUS

Ernest Bleibler, Winterthur, Switzerland, assignor
to Sylvania Industrial Corporation, Fredericks-
burg, Va., a corporation of Virginia

Application April 29, 1930, Serial No. 448,337
In Germany May 2, 1929

3 Claims. (Cl. 34—48)

The invention relates to drying apparatus for cellulose products, more particularly films, skins, strips, webs and the like derived for instance from an aqueous solution of cellulose, for instance sodium xanthate cellulose. The invention is particularly suitable for plants in which the cellulose or similar products obtained from those solutions pass in a continuous manufacturing process from the precipitation baths, cleaning 5 baths and the like on to the drying rollers or cylinders.

The object of the invention is to provide a machine in which the drying process may be accurately adjusted and which supplies an excellent 10 smooth material of good appearance free from scratches or streaks or other faults which render the material unsightly and reduce its value. It has been ascertained that the shrinkage losses during the drying process are very small in the 15 improved apparatus, more particularly in the direction of the width of the film.

By the improved arrangement according to the invention it is possible to avoid in the roller drying apparatus the difficulties arising from the 20 fact that the strip of cellulose in the wet state as indirectly or directly obtained from the treatment baths has little strength and thus easily breaks during the drying process if undue stresses develop. Such stresses may be caused by shocks 25 occurring in the drive of the dryer rollers for instance in consequence of worn out gear wheel drives.

In apparatus with top rollers riding loosely on the cellulose films stresses may be also caused 30 by the cellulose film being squashed by the weight of the rollers resting upon it, and also by the fact that the peripheral velocities of rollers following each other differ from one to the next so that the strip is obliged to slide upon the rollers 35 in order to adapt itself to the speed fluctuations.

According to this invention in a drying apparatus for drying films, strips and the like of cellulose, more particularly of regenerated cellulose, the train of drying rollers or cylinders supporting the film or the like alternately on one side and the other side of the latter and immediately on the drying rollers, consists of two tiers of rollers one above the other and in addition is subdivided into groups, each group comprising an odd number of rollers of one tier and an even number of rollers of the second tier lying between the rollers of the first tier, an end roller of one group being common to an adjacent group and each group being individually power driven.

Irregularities of the drive, noticeable in speed

differences of one roller to the next, are compensated or neutralized, and the rollers of the train of rollers or the group in question are forced to run synchronously or with equal velocity no matter to what fluctuations or thrusts one or the other of the individual drives present is subjected to. Thus the differences in speed in belt drives caused by belt slip may be effectively eliminated.

The arrangement according to my invention in which the individual rollers or some number of the rollers stand simultaneously under the control of a plurality of drives may be realized in various ways.

Preferably a belt drive will be employed as one of the drives in view of the fact that, apart from the slip, the belt drive is substantially free from shocks or thrusts, and also permits of a convenient connection of the differently grouped driving wheels.

In a preferred embodiment of the invention, the groups consist of three rollers, viz., one lower roller and two upper rollers and the groups are individually driven by a belt drive common to all rollers of the group and being driven from a separate source of power, driving means being arranged for coupling said groups to each other, or preferably the top rollers being common to the adjacent individually driven group.

In further preferred embodiments of the invention the rollers of the plant or train of drying rollers or cylinders are subdivided into groups, each group being equipped with a drive of its own and one roller at least being common to two adjacent groups. In a particularly suitable design of this type each group consists of an odd number of rollers, preferably two top rollers and one bottom roller, and each outer top roller is common to the adjacent groups.

In the drawings affixed to my specification and forming part thereof a number of embodiments of my invention are illustrated by way of example. It will be readily understood, however, that my invention is by no means limited to these constructions and that the scope of my invention and the ambit of my appended claims extends to any construction incorporating the broad principle underlying my invention.

In the drawings Fig. 1 shows diagrammatically a train or plant of rollers well known in the art of drying pellicles, strips, films and the like of cellulose or similar products.

Fig. 2 illustrates an embodiment of my invention in side elevation,

Fig. 3 is an elevation from the drive side of the arrangement according to Fig. 2 and

Fig. 4 represents two rollers of the arrangement according to Figs. 2 and 3 with their drives 5 in front elevation.

Referring to Fig. 1 of the drawings it will be observed that the strip or band of cellulose of an indefinite length travels over the rollers of the train or plant of rollers. In Figs. 2 to 4 this 10 band or film to be dried has been omitted for the sake of clearness. The band is here passed over the rollers preferably in the manner shown in Fig. 1. It will be understood, however, that the strip or band may be guided in a different 15 manner, for instance through between the rollers.

From a vat or tank 12, which according to the process of manufacture contains a cleaning, hardening or other bath, for example a band or strip of cellulose 11, is withdrawn over the 20 drying rollers 14, 15 and finally reaches the winding-up reel 17.

In the embodiment illustrated in Fig. 2 in side-elevation, in Fig. 3 in plan, and in Fig. 4 in front-elevation, the belt drives 40, 41 drive 25 by means of the belts 42, 43 groups consisting of three roll members, viz: the bottom rollers 44 or 45 as well as the top rollers 46, 47. On the trunnions of the rollers or cylinders 44 or 45 respectively there is keyed a pulley 50 or 51 30 respectively, while on the trunnions of the top rollers there are mounted two pulleys each 52, 53 one of which, for instance, 52 pertains to the drives 40, 42, the other 53 to the drives 41, 43. All the top rollers are thus directly and the 35 bottom roller indirectly under the control of two drives simultaneously so that undesired mutual movements of the rollers of adjacent groups as well as of the train of rollers or sections of it are entirely precluded. The roller groups may 40 also consist of five, seven and so on members.

Apart from the uniformity of the drive by which the peripheral speed of the rollers desired 45 at any time is ensured still further considerable advantages are realized by the improved arrangement according to my invention. Thus the top roller and the bottom roller may be so securely journaled that no relative motion need be feared, and it is possible to adapt the spacing of the rollers to the conditions prevailing in each 50 individual case. The rollers may be arranged closely together or preferably at such distances apart that when the film breaks it is able to coil itself up on any one of the rollers without braking the rollers or the entire train of rollers, and 55 that on the other hand the rollers may be easily cleaned and the cellulose film threaded through between the rollers without the danger that the hand of the operator might be gripped by the rollers and drawn into the machine.

A still further advantage of the rollers journaled in stationary bearings is that the top rollers as well as the bottom rollers may conveniently be equipped with connecting means for the supply of a heating medium into the rollers or cylinders, for instance for the steam pipes 60, 61, so that all the rollers or cylinders of the train may be brought to the raised temperature desired at the time and temperature differences between successive rollers likely to affect the quality of 65 the fabric are effectively avoided. By heating both rows of rollers or cylinders it is possible to carry out the drying process at moderate temperatures, for instance between 50 and 90°, and with short trains or plants of rollers consisting 70 of a few rollers only.

A still further advantage over the arrangement in which the top rollers rest upon the bottom rollers resides in the fact that, as already pointed out, the cellulose film to be dried is relieved of the weight of the top roller in case this 5 roller rests directly upon the bottom roller or in case the top roller rests loosely on the bottom roller and is maintained at a short distance from the bottom roller by means of spacing rings: the rapid wear of these rings running in the drive 10 state is effectively avoided. The films to be dried run uniformly and smoothly round the rollers, cylinders or drums without any relative movement between film and roller apt to cause scratching or scoring of the surface of the film 15 and thus to affect its appearance adversely.

It will be understood that the invention is not limited to the embodiments described and illustrated by way of example and that various structural changes and modifications may be 20 made without departing from the spirit of my invention, and I desire therefore that the appended claims should be construed in the light of prior knowledge.

Instead of the belt drives shown in the drawings gear drives might thus be provided, since now in consequence of the multiple drive of the individual rollers or groups of rollers according to my invention shocks or thrusts on the individual rollers can no longer occur in such drives 25 and, as already described the speeds of the individual rollers are controlled in a perfect manner while in the known customary drives of the roller or of entire trains of rollers and coupling of these rollers merely by the film to be dried a control of the speed, particularly in trains consisting of a great number of rollers, is quite impossible. Slip losses of the belt or other drives, shocks caused by wear and inaccurate adjustment of gear wheels, cannot possibly be avoided in the 40 known drives and greatly reduce the quality of the final product.

I claim as my invention:—

1. In a drying apparatus for drying films, strips and the like of cellulose, more particularly of regenerated cellulose, the combination of a train of drying rollers adapted to support the film alternately on one side and on the other side of the latter and immediately on the surfaces of the drying rollers, said train of rollers comprising two tiers of rollers one above the other, and in addition, being subdivided into groups, each group comprising an odd number of rollers of one tier and an even number of rollers of the second tier lying between the rollers of the first 50 tier, an end roller of one group being common to an adjacent group and each group being individually power-driven.

2. In a drying apparatus for drying films, strips and the like of cellulose, more particularly of regenerated cellulose, the combination of a train of drying rollers adapted to support the film alternately on one side and on the other side of the latter and immediately on the surfaces of the drying rollers, said train comprising two superimposed tiers of rollers and being subdivided into groups of three rollers, each group comprising one lower roller and the two upper rollers adjacent thereto, each group being individually driven by a belt drive common to all rollers of 65 said group and being driven from a separate source of power, and driving means for coupling said groups to each other.

3. In a drying apparatus for drying films, strips and the like of cellulose, more particularly of re- 70

generated cellulose, the combination of a train of drying rollers adapted to support the film alternately on one side and on the other side of the latter and immediately on the surfaces of the 5 drying rollers, said train comprising two superimposed tiers of rollers and being also subdivided into a plurality of groups of three rollers each, each group comprising one lower roller and the

two upper rollers adjacent thereto, each group being individually driven by a belt drive common to all rollers of said group and being driven from a separate source of power, at least one of the top rollers of each group being common to the adjacent individually driven group. 5

ERNEST BLEIBLER.
